UNITED STATES PATENT OFFICE.

LAURENCE J. BERKELEY, OF RACINE, WISCONSIN, ASSIGNOR TO THE P & M COMPANY,
OF CHICAGO, ILLINOIS, A CORPORATION OF ILLINOIS.

RAIL-ANCHOR.

1,303,239.

Specification of Letters Patent. Patented May 13, 1919.

Application filed July 30, 1918. Serial No. 247,406.

To all whom it may concern:

Be it known that I, LAURENCE J. BERKELEY, a citizen of the United States, residing at Racine, in the county of Racine and State 5 of Wisconsin, have invented certain new and useful Improvements in Rail-Anchors, of which the following is a specification.

My invention relates to a rail anchor or anti-creeper, and particularly to a device 10 adapted for engagement with one flange only of a rail.

A primary object of the invention is to provide a simple, inexpensive rail anchor, which is light in weight, compact, adapted 15 to engage with one flange only of the rail, and which may be rigidly attached to the rail by an engagement that will be permanent, reliable and capable of withstanding any normal creeping pressure.

20 The invention is illustrated in a preferred embodiment, in the accompanying drawings, wherein—

Figure 1 is a fragmentary side elevation of a rail and cross tie with the anchor of my 25 invention in place on the rail.

Fig. 2 is a plan view of the parts shown in Fig. 1.

Fig. 3 is a sectional view on the line 3—3 of Fig. 2.

30 Fig. 4 is an enlarged fragmentary sectional view showing a preferred method of applying the anchor to the rail.

Fig. 5 is a perspective view of the body of the anchor.

35 Fig. 6 is a plan view of the blank from which the locking key of the anchor is made; and

Fig. 7 is a perspective view of the key.

Like characters of reference designate 40 like parts in the several figures of the drawings.

In the drawings the anchor is shown as engaged with one flange 10 of the rail 11 and abutting a tie 12. The body of the anchor 45 consists preferably of a malleable iron casting having upper and lower jaws 13, 14, respectively, which outline a space shaped to receive the flange of the rail. A depending stiffened web or leg 15 abuts the tie. In 50 the lower jaw 14 is provided a key-way 16 which extends, preferably, transversely through the casting and increases in depth inwardly of the recess between the jaws. A flat key 17 is located in the key-way 16, the 55 key being formed from a blank 17^a shown

in Fig. 6, notched at 18, the metal adjacent the notches being bent to form the teeth 19, the notched end of the blank being bent to a curved configuration corresponding to the curve of the bottom of the key-way. 60

The body of the anchor is placed or preferably driven upon the base flange of the rail with the key in the key-way in the position shown in Fig. 4. The outer end of the key is provided with a perforation 20 and 65 in applying the device a tool, outlined at 21, Fig. 4, is inserted in the perforation and the key drawn outwardly through the key-way until the teeth 19 bite into the bottom of the rail, as shown in Fig. 3. The same 70 movement of the tool will bend the outer end of the key so as to lock the same against an inward or retrograde movement.

Obviously the form and arrangement of the parts may be varied considerably without departure from the principle of my invention. Therefore I do not wish to be understood as limiting the invention to the form and construction of the parts shown except as set forth in the appended claims. 75 80

I claim:

1. In a rail anchor, the combination of a rail engaging member and a key arranged between the same and the rail formed with a projection adapted, when the key is moved 85 in the direction of its length, to embed itself in the rail at a point within the vertical edges of the rail.

2. In a rail anchor, the combination of a rail engaging member and a key arranged between the same and the rail formed with a projection adapted, when the key is moved in the direction of its length, to embed itself in the rail at a point within the vertical edges of the rail, said key being adapted to 90 assume a position, when operatively engaged with the rail, in which movement of the key with respect to said rail engaging member is prevented.

3. In a rail anchor, the combination of a 100 rail engaging member and a key arranged between said member and rail adapted, when moved in the direction of its length, to have a biting engagement with the rail, said key being adapted to be bent when in its operative position to prevent movement in a direction to release its hold on the rail. 105

4. In a rail anchor, the combination of a rail engaging member and a key arranged between said member and the rail and 110

adapted, when moved in the direction transversely of the rail, to have a biting engagement with the rail; said key being adapted to be bent when in its operative position to prevent movement in the direction to release its hold on the rail.

5. In a rail anchor, the combination of a rail engaging member formed with a key-way and a key having a projection at one end thereof which is adapted to be embedded in the rail at a point within the vertical edges of the rail when the key is drawn through said key-way.

10. In a rail anchor, the combination of a rail engaging member formed with a key-way and a key having a projection at one end thereof which is adapted to be embedded in the rail when the key is drawn through said key-way, the other end of said key being bendable so as to lock the key with respect to said rail engaging member.

15. In a rail anchor, the combination of a rail engaging member formed with a key-way disposed transversely of the length of the rail and which is deeper at one end than at the other, and a key in said key-way movable lengthwise thereof having on the extremity which is in the deeper end of the key-way a projection adapted to be embedded in the rail.

20. In a rail anchor, the combination of a rail engaging member recessed to form jaws for engaging the top and bottom of the base flange of a rail, one of said jaws being formed with a key-way which extends through the outer end of said rail engaging member, and a slideable key in said key-way, one end of which projects therefrom, the other being formed with a tooth adapted to be embedded in the base of the rail at a point within the vertical edges of the rail.

25. In a rail anchor, the combination of a rail engaging member recessed to form jaws for engaging the top and bottom of the base flange of a rail, one of said jaws being formed with a key-way which extends through the outer end of said rail engaging member, and a slideable key in said key-way, one end of which projects therefrom and is formed with an opening, for the purpose described, the other being formed with a tooth adapted to be embedded in the base of the rail.

30. In a rail anchor, the combination of a rail engaging member recessed to form jaws for engaging the top and bottom of the base flange of a rail, one of said jaws being

formed with a key-way which extends through the outer end of said rail engaging member, and a slideable key in said key-way, one end of which projects therefrom, is bendable and formed with an opening for the purpose described, the other being formed with a tooth adapted to be embedded in the base of the rail.

35. In a rail anchor, the combination of a rail engaging member recessed to form jaws which engage the top and bottom of the base flange of the rail, the lower jaw being formed with a key-way disposed transversely of the length of the rail and which extends through the outer end of said member, a key in said key-way formed on its inner end with a tooth adapted to be embedded in the rail, the other end of which projects beyond the key-way, for the purpose described.

40. In a rail anchor, the combination of a rail engaging member recessed to form jaws which engage the top and bottom of the base flange of the rail, the lower jaw being formed with a transversely disposed key-way which extends through the outer end of said member, a key in said key-way formed on its inner end with a tooth adapted to be embedded in the rail, the other end of which projects beyond the key-way and is perforated and bendable for the purpose described.

45. In a rail anchor, the combination of a rail engaging member recessed to form jaws which engage the top and bottom of the base flange of the rail, the lower jaw being formed with a transversely disposed key-way, the bottom of which at the inner end having a downward inclination, a key in said keyway formed on its inner end with a tooth adapted to be embedded in the rail, the other end of the key projecting in the key-way, for the purpose described.

50. In a rail anchor, the combination of a rail engaging member recessed to form jaws which engage the top and bottom of the base flange of the rail, the lower jaw being formed with a transversely disposed key-way, the bottom of which at the inner end has a downward inclination, a key in said key-way formed on its inner end with a tooth adapted to be embedded in the rail, the other end of the key projecting in the key-way being perforated and bendable, for the purpose described.

LAURENCE J. BERKELEY.
